UNITED STATES PATENT OFFICE.

CHARLES F. FILOR, OF TRENTON, NEW JERSEY.

GARMENT.

1,198,902.

Specification of Letters Patent. Patented Sept. 19, 1916.

Application filed September 29, 1914. Serial No. 864,024.

To all whom it may concern:

Be it known that I, CHARLES F. FILOR, a citizen of the United States, residing at Trenton, in the county of Mercer and State 5 of New Jersey, have invented certain new and useful Improvements in Garments, of which the following is a specification.

This invention relates to improvements in garments and has especial reference to the 10 neckbands of men's shirts, ladies' waists and the like.

The object of the present invention is to so construct the neckband of a garment as to obviate the disagreeable contact of the 15 collar button with the neck of the wearer.

Another object is to accomplish the above without weakening the collar band, and a still further object is to do this in such a manner as not to require the use of any material other than usually employed in the 20 manufacture of an ordinary garment.

With these and other objects in view, my invention consists of the following novel combination and arrangement of parts, hereinafter more fully referred to, illustrated in the accompanying drawing and pointed out in the claim hereto appended.

In the accompanying drawings:—Figure 1 is an inner face view of a portion of the 30 neckband of a shirt and contiguous parts, Fig. 2 is a similar view of that portion of the neckband usually carrying the collar button, and Fig. 3 is a sectional perspective view of the subject matter of the preceding figure.

In carrying out the invention the usual neckband 1 is employed attached to the shirt in the ordinary manner, which, in the present instance, is shown as an ordinary negligée shirt. The side 2 of the bosom is made with the usual button holes having the ordinary reinforcing strip 3. The other side 4 of the bosom has stitched thereto one end of the neckband 1 with the collar button 40 hole 5 formed therein through all of the thicknesses of said band so as not to weaken the collar button hole. The usual button reinforcing strip 6 through which the attaching threads for securing the bosom button 45 tons 7 pass is employed. This last mentioned strip is secured to the garment by stitches 8 which terminate at 15 and is stitched upon the outside of said band along

the row of stitches 8 at the same time the collar band is secured to the shirt. The 55 strip 6 is also stitched along the line 9 across the collar band forming a pocket 10 open at its top and one side. In order that a more secure pocket may be obtained, a couple of stitches may be taken at the point 11, 60 although this is not essential.

It is thus apparent that a pocket open at the top is formed for receiving the back of the collar button usually contacting with the neck of the wearer.

65

Various means have been employed for accomplishing the above object, but heretofore the pocket has been formed from one or more layers of material of which the neckband is formed and thereby weakening 70 the said neckband or by sewing on an additional strip of material.

Having thus described my invention, what I claim is:—

The combination with a garment having 75 a neck portion and a vertical opening extending therethrough, of a neck band consisting of a plurality of strips continuous from end to end of such neck band and mounted on the neck portion of the garment 80 and provided with overlapping ends having collar button holes formed therein arranged to register when the ends are overlapped, a vertical button reinforcing strip secured to the inner side of the garment at one edge 85 of the vertical opening by a row of stitching and extending to the upper edge of the garment neck band to provide a portion overlapping with a portion of the neck band which overlaps the remaining end of said band, said button reinforcing strip being secured to the bottom edge of the neck band by a row of transverse stitching and being secured at its inner edge to said neck band by a row of vertical stitching whereby to 90 form a protective flap between the neck band and the body of the wearer, said flap being free on two adjacent edges of the neck band.

95

In testimony whereof I affix my signature 100 in presence of two witnesses.

CHARLES F. FILOR.
